UNITED STATES PATENT OFFICE.

JAMES LEWIS, OF OTTAWA, ONTARIO, CANADA.

METHOD OF CASTING PRINTING SLUGS.

No Drawing.

Application filed March 11, 1925. Serial No. 14,780.

To all whom it may concern:

Be it known that I, JAMES LEWIS, a subject of the King of Great Britain, and resident of the city of Ottawa, in the Province 5 of Ontario, Dominion of Canada, have invented certain new and useful Improvements in the Method of Casting Printing Slugs; and I do hereby declare that the following is a full, clear, and exact description thereof.

The object of the present invention is to provide a new and improved method of expeditiously and economically making cast slugs for printing reproductions of printed 15 matter, signatures such as appear on stocks, bonds and the like and pictorial representations.

Heretofore in printing work of this kind particularly in the printing of signatures 20 and pictorial representations in large quantities it has been and still is the practice generally to make a large number of electrotypes having the design, to be reproduced, in relief. This method has proved 25 both costly and slow and it is highly desirable to provide a method by which reproductions may be printed in large quantities at a comparatively low cost.

Attempts to solve the difficulty have been 30 made in the past by making steel male dies of the designs to be reproduced and with the dies forming in brass and other suitable metal, matrices in which slugs were cast. These attempts failed however to overcome 35 the difficulty owing to the high cost of making the steel dies.

The present invention provides a solution 40 of the problem by making it possible to make at a minimum cost and in a comparatively short time any desired number of slugs having in their printing faces the design in relief, to be reproduced.

In carrying out my improved method a zinc line etching is first made from the copy 45 which it is desired to reproduce. This is accomplished by coating the zinc with a bichromated fish glue or enamel and the copy photographed thereon. This photograph is then developed and the zinc etched 50 with acid which bites away all portions of the zinc not coated with the enamel, leaving the design in relief.

The etching thus produced is then placed 55 in an electro-plating bath and copper, brass or any other suitable metal is deposited on

the zinc by electrolysis to a depth of approximately one sixteenth of an inch or to whatever depth may be required for the particular kind of type casting machine with which the casting is to be done.

After the desired depth of metal has been deposited the zinc is removed, leaving an intaglio design in the electro-plate constituting a matrix. The zinc is removed by subjecting it to a temperature higher than its 60 melting point of 419° centigrade and considerably lower than the melting point of the metal deposited thereon. The melting points of the copper and brass are respectively 1083° centigrade so that the melting 65 of the zinc in a gas furnace may be readily effected without injuring the matrix when composed of either of the former metals. Any other metal employed should have a melting point in the vicinity of the melting 70 points of these metals.

In order to more readily obtain the separation of the zinc from the matrix during the heating process, graphite may be mixed with the enamel which is deposited on the 75 zinc.

After the zinc has been removed the matrix is backed by any suitable reinforcing metal and is then ready for use in the casting operation. This may be carried out in 80 any desired manner in any of the well-known type casting machines.

From the foregoing it will be seen that it is possible to cast any desired number of slugs bearing in relief the design sought to 85 be reproduced from the one matrix, the cost of making which is comparatively small, and furthermore that the reproductions printed from the slugs will be precise copies 90 of the subject-matter which it is desired to 95 reproduce.

What I claim is as follows:—

1. The method of casting printing slugs and the like consisting in making a zinc etching, making an intaglio impression in 100 a suitable metal with the etching, and utilizing said impression as a matrix for the casting of printing slugs.

2. The method of casting printing slugs and the like consisting in making a zinc 105 etching, electro-plating the zinc etching with a metal having a higher melting point than the melting point of the zinc; separating the zinc etching from the electro-plating by subjecting it to a heat sufficient to melt 110

the zinc but not sufficient to injure the electro-plating, and utilizing the latter as a matrix for the casting of printing slugs.

3. The method of casting printing slugs and the like consisting in making a zinc etching by coating the zinc with an enamel consisting of bichromated fish glue; photographing a design thereon and etching the zinc with a suitable acid to leave the design in relief; depositing a metal having a higher melting point than the melting point of the zinc by electrolysis upon the zinc etching, subjecting the whole to a heat sufficient to separate the zinc from the metal without injuring the latter, and utilizing the intaglio impression thus formed in the metal as a matrix for the casting of printing slugs.

4. The method of casting printing slugs and the like consisting in making a zinc etching by coating the zinc with an enamel

consisting of bichromated fish glue and graphite; photographing a design thereon and etching the zinc with a suitable acid to leave the design in relief; depositing a metal having a higher melting point than the melting point of the zinc by electrolysis upon the zinc etching, subjecting the whole to a heat sufficient to separate the zinc from the metal without injuring the latter, and utilizing the intaglio impression thus formed in the metal as a matrix for the casting of printing slugs.

In testimony whereof I have signed my name to this specification in the presence of two witnesses.

JAMES LEWIS.
